UNITED STATES PATENT OFFICE.

ALBION D. T. LIBBY, OF EAST ORANGE, AND SAMUEL C. McKEOWN, OF NEWARK, NEW JERSEY, ASSIGNEES TO SPLITDORF ELECTRICAL COMPANY, OF NEWARK, NEW JERSEY.

IGNITION-CIRCUIT BREAKER.

Application filed January 25, 1921. Serial No. 439,717.

To all whom it may concern:

Be it known that we, ALBION D. T. LIBBY, a citizen of the United States, residing at East Orange, in the county of Essex, State 5 of New Jersey, and SAMUEL C. McKEOWN, a citizen of the United States, residing at Newark, in the county of Essex, State of New Jersey, have invented certain new and useful Improvements in Ignition-Circuit 10 Breakers, of which the following is a description, reference being had to the accompanying drawing and to the figures of reference marked thereon.

This invention relates to circuit breakers 15 and in particular to circuit breakers forming part of a magneto or electric generator structure used for ignition purposes with internal combustion engines.

Considerable difficulty has been had in the 20 past with the fouling of the contact points of the circuit breaker due to the accumulation of dust, dirt and oil thereon and many attempts have been made to prevent such fouling from taking place, with but poor 25 success.

We have found that with our invention, we have reduced the chance of fouling of 30 the contact points to a minimum and as a matter of fact from several actual tests it has been found that at the end of long runs, the contact points have remained absolutely bright and clean.

It is the main object of our invention to 35 protect the contact points of the circuit breaker against the chances of fouling.

It is another object of our invention to make a structure of this character as cheap and efficient as is possible.

Other and minor objects will appear after 40 reading the following specification and claims in connection with the accompanying drawings in which:

Figure 1 is a view of our circuit breaker shown as a part of a magneto, the magneto 45 being shown only fragmentarily, a portion of the housing enclosing the circuit breaker being broken away and another portion being shown in section to disclose hidden parts.

Figure 2 is a view of the circuit breaker, the outer cover having been removed, and a 50 condenser being shown in outline only.

Figure 3 is a view of another portion of our circuit breaker, a second and inner cover having been removed.

Figure 4 is a section along the line 4—4 55 of Figure 3.

Figure 5 is a section through a fragmentary portion of our circuit breaker.

Figure 6 is a section along the line 6—6 60 of Figure 3, and

Figure 7 is a view of the inner side of 65 our cam cover.

Now referring more in detail to the several figures, 1 indicates a magneto of which the circuit breaker forming our invention 70 is a part. In the present instance the circuit breaker is comprised of; a breaker base section 2, on which is mounted a base plate 3; a cam cover 4 mounted on the base plate, enclosing a cam and a breaker arm actuating mechanism and supporting on the outside of the cover 4, the stationary contact of the circuit breaker; and a breaker cover 5 fitting on the cam cover and housing the contact maker and breaker. 75

The breaker base 2 is secured to the adjustable field structure of the magneto by means of the screws 6, the cup-shaped portion 7 fitting snugly over a boss on the structure as is clearly shown in the patent to 80 Mason 1,226,233, dated May 15, 1917. A lever 8 is secured to the breaker base in any suitable manner so that upon rotating the breaker base, the field structure may be rotated to advance or retard the time of 85 spark, all as will be understood, by those skilled in the art and by referring to the Mason patent. An apron 9 is provided to close an opening in the base of the magneto through which a primary wire is led to the 90 circuit breaker as will be readily understood by referring to the patent hereinabove referred to. The breaker base is provided with a central opening 10 in which is rotatably mounted the flange 11 of the base plate 95 3. The base plate is provided with a pair

of elongated slots 12 and 13, and a pair of screws 14 passing through these slots and tapped into the breaker base 2, serve to bind the base plate to the breaker base in any desired adjusted relationship. This adjustment is provided in order to adjust the relative position of the breaker mechanism with respect to the rotor, so as to get the maximum spark value out of the magneto. In order to permit the passage of the primary wire through the breaker base and plate, two aligned slots 15 and 16 are provided, the slot 15 in the base plate being wider than the slot 16 in the breaker base so that the opening may not be restricted upon rotation of the two parts relative to one another. Rigidly secured upon the base plate are two posts 17 and 18, the post 18, preferably made of steel, serving to support a bronze oscillatable bearing 19, said bearing having rigidly secured thereto a bumper arm 20 carrying a bumper 21 adapted to come in contact with and to be actuated by a cam 22 on the end of a shaft 23, said shaft being part of the magneto structure, said cam and shaft extending through the central opening afforded by the flange 11. A spring 24 secured to the post 17 and the bumper arm 20 urges the arm to rotate in a counter-clockwise direction as viewed in Figure 3. The bearing 19 is provided with a shoulder 25 upon which rests a felt gasket 26, said gasket closing an opening 55 in the cam cover 4 through which the bearing extends and being encompassed by a hollow 27 in the inner side of said cover.

The cam cover 4 fits snugly onto a shoulered portion 28 of the base plate 3 and is firmly held thereto by means of two screws 29 and 30 passing through a hole 56 and a bushed hole 52 in the cover and tapped into holes 31 in the base plate. Mounted upon the cam cover and insulated therefrom by a fibre sheet 32 is a bracket plate 51 secured to the cover by means of a screw 33, it being understood that both the screws 30 and 33 are suitably insulated from the cam cover 4 as by the bushings in the hole 52 and the bushing 54. Mounted on the bracket plate 51 and in electrical engagement therewith is a grounding post 34 provided with a shoulder 35 resting against the exposed surface of the plate 51 and passing through a bushing 53 in the cam cover 4, said grounding post being secured in place on the underside by means of a nut. Either the grounding post or the screw 33 may be made sufficiently long for attachment therewith of the primary wire as will be readily understood and thereby include the bracket plate as a portion of the electric circuit. The grounding stud also serves as a support for the breaker cover 5, said cover having an insulating bushing 36 therein to prevent electrical engagement of the cover with the grounding post and said

cover fitting snugly on a shoulder 37 on the cam cover. A thumb nut 38 screwed onto the post 34 affords a means of attaching a grounding wire to the post, a switch being inserted in the wire to render the magneto inoperative when desired and at the same time binds the breaker cover onto the cam cover.

Secured in place on the bearing 19 by means of a suitable lock washer and a nut 39, and held against rotation with respect to the bearing 19 by means of a shoulder, portion 40 is a breaker arm 41 carrying a contact point 42, said contact point co-operating with a contact point 43 adjustably carried in a bracket 44 bent up from the plate 51. A spring arm 45 secured to a post 46 mounted directly on the cam cover bears against a nib 47 on the bearing 19 to prevent longitudinal movement of said bearing on the stud. It can now be seen that the bumper 21 is actuated by the cam 22 that the contact points through bumper arm 20, bearing 19 and breaker arm 41 will alternately open and close the circuit, it being understood that the opposite terminal of the primary and the contact point 42 are grounded.

A bracket 48 on the insulated bracket plate 51 and a stud 49 on the grounded cam cover serve to support a condenser 50 of any suitable type, said condenser being thus bridged across the contact points.

We have thus provided a circuit breaker for a magneto in which the contact points are isolated in a compartment formed by the breaker cover and the top of the cam cover, separate from the cam and bumper, which latter are enclosed within the cam cover and which constitutes the operating mechanism for the circuit breaker. Thereby oil and grease thrown from the magneto shaft and other operating structures are excluded from the compartment in which the contact points are housed. It will be further noted that in use and as shown in Figure 1, the contact points are in a horizontal plane, above the plane of the only opening leading to the compartment in which the circuit breaker is housed, so that if by chance any foreign material should enter said compartment through this opening, gravity would cause the material to move in a direction away from the contact points.

Having thus described our invention, what we claim is:

In a circuit breaker, a breaker base, a base plate adjustable thereon and secured thereto, a cam cover mounted on said base plate, means for securing said cam cover to said base plate, an insulated bracket plate mounted on the cam cover, a grounding post mounted on said bracket plate, said grounding post being rigidly held in place in electrical engagement with the insulated bracket plate, a circuit breaker cover mounted on the cam cover positioned by and insulated from

the grounding post, means for securing the last mentioned cover in place, a plurality of studs mounted on the base plate, a bearing mounted on one stud having rigidly secured thereto a bumper arm, a bumper in said arm, a cam mounted on a shaft extending into the cam cover cooperating with said bumper, spring means secured to the bumper arm and the remaining stud to urge the bumper into engagement with the cam, said bearing ex-

tending through a packed opening into the compartment enclosed by the circuit breaker cover, and a contact carried by said bearing cooperating with a contact mounted on the bracket plate.

15

In testimony whereof, we have hereunto affixed our signatures.

SAMUEL C. McKEOWN.
ALBION D. T. LIBBY.
